[57] CLAIM

The ornamental design for a personal vehicle, as shown.

DESCRIPTION

FIG. 1 is a perspective view of a personal vehicle showing our new design with the windshield wiper and bumper illustrated in phantom line;

FIG. 2 is a right side elevational view thereof;

FIG. 3 is a left side elevational view thereof;

FIG. 4 is a top plan view thereof;

FIG. 5 is a front elevational view thereof;

FIG. 6 is a rear elevational view thereof;

FIG. 7 is a perspective view of another personal vehicle showing a second embodiment of our new design with the windshield wiper and bumper illustrated in phantom line;

FIG. 8 is a right side elevational view of FIG. 7;

FIG. 9 is a left side elevational view of FIG. 7;

FIG. 10 is a top plan of FIG. 7;

FIG. 11 is a front elevational view of FIG. 7; and,

FIG. 12 is a rear elevational view of FIG. 7.
